(57) **CLAIM**

The ornamental design for a bra, as shown and described.

DESCRIPTION

FIG. 1 is a front, right and bottom perspective view of a bra showing my new design;

FIG. 2 is a rear, left and top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is rear view thereof shown in an environment of use. The broken line showing of the arms, torso and neck in FIG. 9 is for the purpose of illustrating portions of the environmental structure and forms no part of the claimed design.
